UNITED STATES PATENT OFFICE.

NELSON L. JACOBUS, OF WEST ORANGE, NEW JERSEY, ASSIGNOR TO ELECTRO-CHEMICAL ENGRAVING CO., A CORPORATION OF NEW YORK.

DESIGN FOR A BOTTLE-CAP REMOVER.

48,550.

Specification for Design.

Patented Feb. 15, 1916.

Application filed April 10, 1915. Serial No. 20,582. Term of patent 7 years.

To all whom it may concern:

Be it known that I, NELSON L. JACOBUS, a citizen of the United States, residing at West Orange, in the county of Essex and State of New Jersey, have invented a new, original, and ornamental Design for Bottle-Cap Removers, of which the following is a specification, reference being had to the accompanying drawing, forming part thereof.

In the drawing: Figure 1 is a plan view, and Fig. 2 is an edge view of the bottle cap remover.

I claim:

The ornamental design for a bottle cap remover, substantially as shown.

NELSON L. JACOBUS.
